UNITED STATES PATENT OFFICE.

ALEX TAUB, OF DETROIT, MICHIGAN, ASSIGNOR TO GENERAL MOTORS CORPORATION, OF DETROIT, MICHIGAN, A CORPORATION OF DELAWARE.

OILING SYSTEM FOR INTERNAL-COMBUSTION ENGINES.

Application filed December 12, 1923. Serial No. 680,177.

My invention relates to lubricating systems for internal combustion and similar engines of the type wherein the oil is supplied to a plurality of bearings to be lubricated

5 under pressure from a suitable oil forcing pump; and particularly to systems of the class above mentioned and wherein the oil thus supplied is forced through passages extending along a valve operating shaft and 10 the crank shaft of the engine, and is led off from the passage in said crank shaft through suitable ports and to several crank pin bearings to be oiled.

In systems of the kind above mentioned it 15 has often happened that, because of the structural features of the system as a whole, the pressures at the several bearings to be oiled varies considerably, with the result that different quantities of oil are supplied 20 to the bearings, some receiving more oil than is necessary, and others less or even none at all; and the object of my invention illustrated in the drawings and hereinafter described and explained is to provide a system 25 of the forced feed type in question wherein the oil will be distributed more uniformly, as regards quantities, and at more nearly equal pressures to and at the several bearings to be lubricated, than in prior lubricating 30 systems of the type herein referred to.

The preferred form of my invention is illustrated in the drawings accompanying and forming a part of this specification; although my invention may be embodied in 35 various other forms or which upon analysis will be found to be modifications of the particular form thereof illustrated, all intended to be covered by the patent to be secured therefor; so long as such other forms come 40 within the scope of the claims which conclude this specification and wherein the distinguishing features of my invention are particularly enumerated.

In the drawings accompanying and forming 45 a part of this specification, and wherein like reference numerals designate the same parts and features in the several views:

Figure 1 is a view showing my invention 50 as applied to a multiple cylinder internal combustion engine, the view being for the most part in side elevation and so much only of the engine as is necessary to an understanding of my invention being illustrated.

55 Figure 2 is a view showing a section upon

a vertical transverse plane indicated by the line 2, 2, Figure 1, with parts broken away in order to better show the relationship of my invention to the engine.

Figure 3 is a view showing the engine, 60 equipped with my invention in elevation, and as seen from a position to the right of Figure 1.

Figure 4 is a fragmentary view showing a section upon vertical longitudinally extending planes indicated, approximately, by the broken line 4, 4, Figure 3.

Figure 5 is a view like unto Figure 3, but showing my invention modified as regards certain features thereof, as will hereinafter 70 appear.

Figure 6 is a view similar to Figure 4, but showing a section upon planes indicated, approximately, by the broken line 6, 6, Figure 75 5.

Figure 7 is a detail sectional view taken upon a vertical transverse plane indicated by the line 7, 7, Figure 4.

Referring now to the drawings, the reference numeral 10 designates, conventionally, 80 a multiple cylinder internal combustion engine block having, in this particular case, six cylinders arranged side by side within which pistons not shown operate, and whereby a six throw crank shaft is driven through 85 piston rods 11, as is usual in internal combustion engines employed to drive motor driven vehicles.

The lower end of the cylinder block is enlarged to provide a crank case, and is provided with transversely extending bearing supporting members 12, 14 adjacent the two ends thereof, and with a third transversely extending member 13 between said end members and centrally disposed relative 95 to the length of the crank case. These members ordinarily take the form of webs which, in addition to providing supports for the bearings hereinafter referred to, serve to connect the sides of the crank case together 100 and to stiffen the cylinder block structure as a whole.

The bearing supporting members 12, 13 and 14 are provided with aligned bearings 15; and the numeral 16 designates the valve operating or cam shaft of the engine, which shaft has a passage 17 within and extending longitudinally thereof, as shown, the ports 18 leading from said passage to the periphery of the shaft at the bearings afore- 110

said; and through which ports oil supplied to the passage extending along said valve operating shaft under pressure escapes to the bearings 15, thus lubricating the said 5 bearings.

The crank shaft of the engine is rotatable in bearings 19 supported also by the transversely extending bearing supporting members 12, 13 and 14, and is provided with a 10 plurality of crank pins 20, six in the embodiment of my invention herein illustrated and described; although other numbers may 15 obviously be used according to the number of cylinders in the engine block. The crank shaft is provided with a continuous passage 21 extending longitudinally thereof and through the several crank cheeks, and along the several crank pins, and which passage is provided with ports 22 leading to the 20 peripheral surface of the shaft at the main crank shaft bearings 19 and with ports 23 leading from said passage to the bearings between the crank pins 20 and the lower 25 ends of the piston rods 11; from which it follows that oil supplied through the ports 22 and to the passage 21 under pressure, flows to and lubricates the several crank pin 30 bearings of the engine.

Secured to the end of the crank case adjacent the bearing supporting member 14 is a 35 dished cover plate 24 which encloses the usual two to one gears 25, 26 whereby in four stroke cycle engines the valve operating shaft is driven from the crank shaft of the engine. Secured to this cover plate in the 40 form of my invention illustrated in Figures 1 to 4, and 7, is a pump casing casting 27 recessed to provide an interior chamber in which the intermeshing impellers or gears 45 28, 29 of an ordinary geared rotary pump operate. The inlet to the pump is designated by the reference numeral 30; and the impeller or gear 28 is secured directly upon the end of the valve operating shaft 16 and 50 is driven thereby, and the discharge of oil from the pump is through a conduit 31 formed integrally with the pump casing 27 and discharging into the passage 17 which extends along the valve operating shaft.

55 In view of the premises it follows that oil under pressure supplied to the passage 17 by the oil pump will flow along the same, and out therefrom through the several ports 18 and to the bearings 15 wherein the valve operating shaft is supported, thus lubricating the said bearings. The oil then flows in 60 three separate streams from the bearings 15 through passages 32, 33 and 34 extending along the bearing supporting members 12, 13 and 14 and to the crank shaft bearings 19, thus lubricating said bearings by three separate and independent streams of oil all under the same pressure, as all lead from the 65 passage 17 which extends along the valve operating shaft. In the form of my invention

70 tion illustrated the ports 18 lead into annular channels or grooves in the valve operating shaft 16 so that the supply of oil to the bearings 15 is continuous, and continuous also to the crank shaft bearings 19 as the 75 passages 32, 33 and 34 always communicate with the channels into which the ports 18 lead. The ports 22, however, communicate with the passages 32, 33, 34 only once each rotation of the crank shaft, so that the supply of oil to the passage 21 and to the crank pins 20 is intermittent; although it will be appreciated that a continuous supply to the crank pins and piston rod bearings may be secured by providing grooves either in the 80 bearings 19 or in the crank shaft, and with which the ports 22 and the passages 32, 33 and 34 communicate.

85 In some cases it is sufficient to supply oil to the valve operating and crank shaft bearings in separate streams derived from a hollow valve operating shaft as above explained; the crank pin bearings being then oiled by scoops upon the lower ends of the connecting rods as in splash oiling systems. 90 My invention in its more comprehensive form, however, and as hereinbefore pointed out, contemplates the use of a crank shaft having a continuous passage extending along 95 the same, such as the passage 21 shown and above described. In such cases the oil which is under pressure at the several main crank shaft bearings flows through the ports 22 and into the passage 21, and along and out from said passage through the ports 23, thus lubricating the several crank pins 20 and, in a further carrying forward of my invention, from the crank pins along the connecting rods and to the wrist pin bearings 100 between the upper ends of said rods and pistons; it being obvious that the pressure within and along the passage 21 and at the several crank pin bearings is equalized and substantially uniform, because of the three 105 separate conduits 32, 33 and 34 all communicating with said passage, and in which conduits the oil is under the same pressure because all of them communicate with the 110 passage 17 in the cam shaft 16.

115 A branch passage 35 leads from the passage 34 and past a loaded valve 36, and to a pipe 37 the discharge end of which is above and adjacent the gears 25, 26 to thereby oil 120 said gears. Obviously oil is discharged through the pipe 37 whenever the pressure in the passage 17 and conduits 32, 33 and 34 rises above the pressure determined by the spring 381 which acts to close the valve 36 and, while the said spring obviously permits the valve in question to open when the speed 125 of the engine reaches a predetermined rate and prevents a further increase in pressure in the oiling system at higher speeds, my invention does not necessarily include the use 130 of a pressure limiting by-pass such as is

formed by the passage 35 and the spring pressed valve 36 and is not limited to a system wherein a constant pressure is present in a part thereof, or in the system as a whole.

- 2 If the by-pass is not used then obviously the pressure in the system is dependent, approximately, upon the speed of the engine, and, the parts being properly designed, will be sufficient to insure proper lubrication at the 10 lowest speed at which the engine will ordinarily operate; while the volume of oil discharged from the pump, its concomitant pressure, and the quantity of oil supplied to each bearing will increase with the speed of 15 the engine, thus securing more copious lubrication at high speeds, which is a feature of advantage in lubricating systems for internal combustion engines.

Figures 5 and 6 show a different form of 20 oil pump than the form shown in the other figures although it operates precisely as in the preferred form hereinbefore described in that it forces oil into and along the hollow cam shaft of the engines and to the crank 25 shaft bearings. In this form of my invention the end cover plate 38, which is in all essential particulars the equivalent of the cover plate 24, is provided with a recess at 39 so shaped as to provide a pump chamber 30 for the oil pump made up of intermeshing gears 40, 41; the first secured to the end of the cam shaft 16 and driven therefrom and the latter rotatable upon a stud 42 extending through an opening in a cover plate 43 which 35 closes the pump chamber 39. The inlet conduit 44 leads from the oil pan 45 of the engine to the pump chamber, and the pump discharges through a passage 46 in the cover plate 43 and into and along the passage 17 40 in the valve operating shaft 16, the same as in the form of oil pump hereinbefore first described.

Having thus described and explained my invention, I claim and desire to secure by 45 Letters Patent:

1. In a lubricating system for internal combustion engines and in combination with a crank shaft supported in bearings disposed one adjacent each end thereof and in an intermediate bearing between said end bearings, said shaft having a plurality of crank pins, and a passage extending along the same and ports at each of said bearings through which oil may flow therefrom and 50 into said passage, and having also other ports at said crank pins through which oil from said passage is supplied to said pins; a valve operating shaft supported in end and intermediate bearings, and having annular 55 grooves at said bearings, and a passage extending longitudinally thereof and ports

leading from said passage into said grooves and through which oil may flow from said passage to said valve operating shaft bearings; separate and independent oil supply 65 conduits leading one from each valve operating shaft bearing to a crank shaft bearing; and an oil supply pump comprising a rotatable member mounted directly upon one end of said valve operating shaft and arranged to 70 discharge oil into and through the passage aforesaid extending along said shaft.

2. In a lubricating system for internal combustion engines and in combination with a crank shaft supported in bearings disposed one adjacent each end thereof and in an intermediate bearing between said end bearings; a valve operating shaft supported in end and intermediate bearings, and having annular grooves at said bearings, and a 80 passage extending longitudinally thereof and ports leading from said passage into said grooves and through which oil may flow from said passage to said valve operating shaft bearings; separate and independent 85 oil supply conduits leading one from each valve operating shaft bearing to a crank shaft bearing; and an oil supply pump comprising a rotatable member mounted directly upon one end of said valve operating 90 shaft and arranged to discharge oil into and through the passage aforesaid extending along said valve operating shaft.

3. In a lubricating system for internal combustion engines and in combination with a crank case having two transversely extending bearing supporting members located one adjacent each end thereof, and a third transversely extending bearing supporting member disposed between said end bearing members; a valve operating shaft rotatable in bearings supported by said bearing supporting members, and having annular grooves at said bearings, and a passage extending longitudinally thereof, and ports leading from said passage into said grooves and through which oil flows from said passage to said bearings; an oil pump having a rotatable oil forcing member secured directly to and driven by said valve operating shaft, and which pump is arranged to discharge into the passage aforesaid extending along said shaft; a crank shaft rotatable in bearings carried also by said transversely extending bearing supporting members; and means for providing a plurality of passages leading one from each of the bearings for said valve operating shaft to one of the bearings aforesaid wherein said crank shaft is rotatable.

In testimony whereof I affix my signature.

ALEX TAUB.
